(57) **CLAIM**

We claim the ornamental design for a portable electronic device with graphical user interface, as shown and described.

DESCRIPTION

FIG. 1 is a front view of a portable electronic with graphical user interface in a longitudinal direction showing our new design; and,

FIG. 2 is a front view of another embodiment of a portable electronic with graphical user interface in a longitudinal direction showing our new design.

The broken lines showing the portable electronic device and portions of graphical user interface, illustrate environment structure, form no part of the claimed design.
